Primary Examiner — Anhdao Doan(74) *Attorney, Agent, or Firm* — Kilpatrick Townsend & Stockton LLP(57) **CLAIM**

The ornamental design for an assay processing system, as shown and described.

DESCRIPTION

FIG. 1 is a front perspective view of the assay processing system showing our new design;
FIG. 2 is a rear perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof;
FIG. 8 is a bottom plan view thereof; and,
FIG. 9 is an underside rear perspective view thereof.
The broken lines immediately adjacent the shaded areas represent the bounds of the claim, while all other broken lines are directed to environment the broken lines form no part of the claimed design.
